United States Patent Office.

JOHN MARTINO, JACOB BEESLEY, AND JOHN CURRIE, OF PHILADELPHIA, ASSIGNEES TO ORR, PAINTER & CO., OF READING, PENNSYLVANIA.

Design No. 2,953, dated March 17, 1868.

DESIGN FOR A COOK'S STOVE.

The Schedule referred to in these Letters Patent and making part of the same.

TO ALL WHOM IT MAY CONCERN:

Be it known that we, JOHN MARTINO, JACOB BEESLEY, and JOHN CURRIE, of the city and county of Philadelphia, and State of Pennsylvania, have originated a new Design for Cooking-Stoves, of which the following is a full, clear, and exact description, reference being had to the accompanying photographs, making a part of his specification. In the accompanying photographs—

Figure 1 is a perspective view of the stove.

Figure 2 is a face view of the back-plate D.

Like letters in all the figures indicate the same parts.

On the sides, A, are the oven-doors, B, which have a raised panel, d, of elliptical form, surrounded by a wreath, a, which is on the flat surface of the door. Within the wreath, and on the raised surface, is an egg-moulding, b. In the middle of the panel there is a rope-moulding, c, surrounded by long beads, d, and dots, e, alternately arranged. The panels C' of the small doors B' of the sides A are similar to those of the doors B, with the exception that they have not the wreath a, beads d, and dots e, and that they have corner ornaments, f, on their flat surface. The panels C'' of the fire-doors B'' are similar to the panels of the small side doors B', with the exception that they have not the rope-moulding c. The back-plate D, shown detached in fig. 2, has a panel, C''', similar to the panel C of the door B, with the exception of the rope-moulding, and the addition of the small ornaments g projecting outward from the wreath a, and vertical ornaments g'. The feet E have an elliptical moulding, h', and a ruffle, i, at top, at each side of the wreath. The stopper F has an ornament, j, running from end to end. The wings on each side of the feed-door G have small ornaments, k. The upper front H has an ornament, l, running up and down on each stile m. The panel I, on the lower rail of the sides A, has the name of the firm, "Orr, Painter & Co." There is an ornament, n, at each end of the panel on the flat surface of the side, and running wave ornaments around the name. The top rails of the sides have a scroll or ornamental name-plate. The name of the stove, "Excelsior Penn," is also on the front, immediately over the fire-doors B''. The date of the patent is on the feed-door G.

What we claim as our invention, and desire to secure by Letters Patent, is—

The design for cooking-stoves, as shown and described.

In testimony whereof, we have hereunto set our hands and affixed our seals, this 19th day of March, 1867.

JOHN MARTINO. [L. S.]

JACOB BEESLEY. [L. S.]

JOHN CURRIE. [L. S.]
